UNITED STATES PATENT OFFICE.

EDWARD F. SMITH, OF ROCHESTER, NEW YORK, ASSIGNOR TO JOSIAH ANSTICE, OF ROCHESTER, NEW YORK.

SLICER.

No. 892,192.

Specification of Letters Patent.

Patented June 30, 1908.

Application filed November 8, 1905. Serial No. 286,380.

To all whom it may concern:

Be it known that I, EDWARD F. SMITH, a citizen of the United States, residing at Rochester, in the county of Monroe and State of New York, have invented certain new and useful Improvements in Slicers, of which the following is a specification, reference being had therein to the accompanying drawing.

My invention relates to improvements in slicers, and pertains particularly to a machine in which a rotary swinging knife is used.

The object of my invention is to provide a slicer of this character, in which a rotary swinging knife is used, and in which the knife travels slowly during the cutting action and rotates very rapidly, and travels very rapidly during the return movement and rotates at a decreased speed, thus increasing the cutting power of the machine and making as rapid cutting machine as if the cutter traveled at the same rate of speed during both the cutting and return strokes.

Another object of my invention is to provide a machine of this character, in which a more perfect feed is accomplished, and the adjustment of which is such that a slice varying from one-fiftieth (1/50) of an inch to eighteen-fiftieths (18/50), may be readily cut, and the exact thickness of the slice readily determined.

A further object of my invention is to provide a sharpening means for the rotary cutter, which is adapted to be set in operation during the operation of the machine, without interfering at all with the merits of the cutter.

A still further object of my invention is to provide a cutter of this character, in which various adjustments are obtained, as hereinafter fully described.

In the accompanying drawings, Figure 1, is an enlarged side elevation of my improved cutter showing the balance wheel and the hand-operating means removed, and showing the cutter at the end of the cutting stroke. Fig. 2, is an enlarged side elevation of the same as Fig. 1, only showing the cutter at the beginning of the cutting stroke. Fig. 3, is a top plan view of Fig. 2, with the cutter at the beginning of the cutting stroke. Fig. 4, is a side elevation, looking from the opposite direction, and showing the cutter at the end of the cutting stroke the same as Fig. 1. Fig. 5, is a transverse vertical sectional view. Fig. 6, is a detached perspective view of the feed carriage, showing a piece of meat held there-

on. Fig. 7, is an enlarged perspective view of that portion of the cutter showing the sharpener thrown down, and engaging the cutter for sharpening the same. Fig. 8, is an enlarged vertical sectional view of the rotary knife. Fig. 9, is a vertical sectional view through the lower end of the blade-carrying arm showing the eccentric ring for tightening the chain.

Referring now to the drawings, 1 represents a base which, as shown, is supported upon legs 2 and 3, which support the base a slight distance above the table or stand upon which the slicer is to be placed. The said base 1 has bolted thereto at its rear face, by means of bolts 4, see Fig. 5, the rearwardly-extending feed carriage supporting table 5 which is provided at its rear end with the downwardly extending foot 6, and supports the table in a horizontal plane. The base 1, flush with its forward or outer end, is provided with an upwardly extending frame 7 which is adapted to support the gear, etc., of the cutting mechanism, as I will now proceed to describe. The said frame 7, as shown, is of an enlarged form, and is provided adjacent one side with the opening 8 through which the meat or bread is to be fed from the feed carriage. The lower edge of said opening 8 is in a straight horizontal line with the table 5, and is provided with an outwardly-extending horizontal flange 9 of hard steel, and forms the surface against which the rotary knife acts in cutting. The said flange is in a horizontal plane with the upper face of the carriage-supporting table 5. The frame 7, as the edge opposite that in which the opening 8 is formed, is provided with an outwardly and inwardly-extending arm 10 in which is journaled the shaft 11 which carries on the inside of the arm 10 a pinion 12. The said shaft 11 on the outside of the arm is provided with a balance wheel 13 which is provided with the handle 14 by means of which the cutter is operated. The said arm 10 is provided at its upper edge with the upwardly-extending curved arm 15 in which is journaled a shaft 16 to which is keyed on the outside of the arm, a gear wheel 17 which meshes with the small pinion 12. The said gear 17 carries on the inside thereof a larger gear 18 which meshes with a pinion 19 loosely carried by the shaft 20. The said shaft, as shown in Fig. 5, is of an elongated form, and is journaled in an elongated bear-

ing 21 carried by and made as a part of the upper end of the frame 7. The said pinion on the inside is provided with an elongated sleeve 22 which carries at its inner end the sprocket wheel 23, which is removably supported to the flange 24 by means of screws 25.

Loosely mounted upon the shaft 20 between the sprocket wheel 23 and the elongated bearing 21, is a downwardly-extending arm 26 which is fastened to the shaft 20 by means of a set screw 26', and a pin 26² carried by the shaft, and resting in recesses in the arm, and said arm is curved outwardly at 27 so as to allow the free passage of the knife thereby, as hereinafter more fully described. The said arm, at its extreme lower end is provided with an outwardly-curved or bent portion 28 which is provided with an enlarged central opening 75 extending transversely therethrough and in which rests a sleeve or eccentric 76 which is of a length equal to the thickness of the arm, as shown in Fig. 5. The said sleeve is provided with an eccentrically-arranged opening 77 extending longitudinally therethrough, and which forms the eccentric sleeve. Snugly fitting within said eccentrically-arranged opening is the shaft 29 which extends inward and upon which the rotary knife is mounted, as herein-after more fully described. The portion 28 of the arm is provided with an opening 78 through which is screwed the set screw 29', said set screw passing through a segmentally-arranged opening 79, and bearing directly against the shaft 29, and said set screw holds the shaft against the opposite side of the eccentric opening and frictionally holds the eccentric within the arm. The outer end of the shaft has an opening therein into which passes a screw 80 for holding the washer 81 to the shaft, see Fig. 1, and thus limiting the outward movement of the eccentric within the arm. The shaft 29 as shown, extends inwardly beyond the arm 15 and is provided with a sleeve 30 which is loosely mounted thereon, and said sleeve 30 engages the inner edge of the eccentric 76 and limits the inward movement thereof.

From the foregoing description, it will be seen that by loosening the set screw 29' and turning the eccentric the shaft 29 is moved to or from the pivotal point of the arm, and the sprocket wheel carried by said shaft, as hereinafter more fully described, is also moved to or from said pivotal connection, and the chain passing over the sprocket wheel is tightened or loosened as desired.

The inner end of the sleeve is provided with a knife holder 31 which is rigidly secured thereto, and as shown, is formed of a disk-shape and has its inner face slightly concaved. The outer periphery of said knife holder is provided with a circumferential groove or recess 31², in which rests the circular cutter blade 31' which is secured to the holder by

screws 31⁴ which have their heads countersunk in depressions in the blade, so that the outer face of the screws are flush with the cutter blade. Said sleeve 30, as shown, is of an elongated form and provided adjacent the knife on the outside with a sprocket wheel 32, which is also rigidly carried by the sleeve 30. Passing around the sprocket wheel 32 and the sprocket wheel 23 is a sprocket chain 33, and by means of the gearing heretofore described, it will be seen that the sleeve 30 is caused to revolve very rapidly, and thus the rotary knife is also caused to rapidly revolve.

The knife as before described, is carried by the swinging arm 26, and is adapted to be swung across the opening 8, and the knife also rapidly revolving during its swinging movement. The shaft 16 on the inside of the arm 15 is provided with a crank arm 34 which has its outer end pivotally connected to a link 35, which has its outer end pivotally connected to the arm 26 at 36, which is at a point intermediate its ends, and thus the arm 26 is reciprocated back and forth across the opening 8.

As shown in Fig. 1 of the drawings, the knife is at its full outer stroke and the continued rotation of the gear 17 causes the pivotal point between the arms 34 and 35 to move off of a dead center, and the positioning of the shaft 16, 20 and the pivotal connection of the swinging arm 26 is such that the link 35 allows the arm 26 to have a more rapid motion, thus allowing the same to travel backward across the opening 8 at a much greater rate of speed than it travels forward, and bringing the knife back beyond the opening 8, so that the meat or bread may be fed forward through the opening. The backward movement of the knife being in the same direction of the travel of the gear 23, it will be seen that the knife will rotate at a less rate of speed during its backward movement than the forward movement, thus increasing the cutting action of the knife during its forward movement.

The end of the link 35 beyond its pivotal connection with the crank 34, is provided with an enlarged extended end 36' which is provided with an outer bearing surface 37 which is adapted to engage the roller 38 carried by the pivoted arm 39 of the feed mechanism, and said surface is adapted to raise the said pivoted arm 39 and operate the feed mechanism, as hereinafter more fully described. The said lever is shown raised by the extended bearing surface of the links in Fig. 2, while in Fig. 4, the said pivoted lever or arm 39 is in its downward movement. The arm 39 is pivoted to an extension 39' of the frame 7.

The arm 26 is provided with an outwardly-extending lug 40, to which is pivotally connected the arm 41, which is provided at its outer end with a sharpening material 42

which is adapted to engage the outer cutting edge of the knife, and sharpen the same. In order to hold the said end of the arm 41 carrying the material, firmly upon the blade, I provide the inner end of the arm with the two flat surfaces 43 and 44 at right angles to each other, and adjacent said arm is a flat leaf-spring 44' which is adapted to bear upon said flat surfaces of the arm 41, and thus said arm is either held in the position shown in Fig. 1, or in the position shown in Fig. 7, and in both positions the arm is firmly held.

The feed carriage supporting table 5 is provided with a longitudinally-extending groove or slot 44² in which rests or extends a longitudinally-extending rib 45 carried by the underside of the carriage 46. The said carriage consists of a flat plate 46 which rests firmly upon the table 5, and carries the rib 45, but is held a slight distance above the same by the ribs 47 and 48 at each side. The carriage adjacent its forward edge, is provided with upwardly-extending teeth 49 which extend entirely across the plate 46, and are adapted to enter and prevent the meat from slipping on the carriage. The said carriage at each side adjacent its forward end, is provided with upwardly-extending ears 50 in which are rigidly secured the upwardly extending standards 51, which are provided on their inner faces with the ratchet teeth 52. Slidably mounted upon said standard is a follower 53 which has pivotally secured to its under face, the engaging bar 54 which is provided with teeth 55 which are adapted to enter the meat and firmly hold the same on the carriage. The said bar 53, adjacent the standards, is provided with upwardly-extending spring pawls 56 which are normally held in engagement with the ratchet teeth 52 of the bars 51, and thus the follower is held in its downwardly adjusted position. The said pawls 56, as shown, are in the form of a trigger, and thus can be pulled down so that the springs 57 will hold the triggers in an inward position, so that the follower can be readily raised for inserting the meat or bread under the same. The follower is provided with an operating handle 53' by means of which it is raised for inserting the bread or meat.

The table 5, adjacent one side, has a worm 58 rotatably mounted thereon, and said worm being in a plane slightly above the table. The carriage 46 on the side adjacent the worm, is provided with a horizontally-pivoted member 59 which is pivoted at 60, and has its edge provided with worm teeth 61 which are adapted to mesh with the worm 58, and thus the rotation of the worm causes the carriage to be fed towards the knife. The said member 59 has a spring 62 connected to the end thereof, and so positioned that it will either hold the member in or out of engagement with the worm. The said member 59 is pro-

vided with an upwardly extending operating pin 63 by means of which it can be readily thrown in or out of engagement with the worm. As shown, the worm is mounted in ears 64 carried by the table, and the inner end is provided with a ratchet disk 65. The worm 58 adjacent one end is provided with a cut-away portion 58' which stops the feed of the carriage when the member 59 reaches the said space.

Loosely carried by the extreme inner end of the worm 58 is an arm 66 which carries a pivoted pawl 67 which is normally held in engagement with the ratchet disk 65 by means of the spring 68, and thus the upward movement of the arm 66 causes the pawl to rotate the ratchet disk, which in turn rotates the worm, and causes the carriage to be fed towards the knife. The arm 66 intermediate its ends, has pivotally connected thereto at 69, the upwardly-extending link 70, which is pivotally connected at 71 to the arm 39, and thus the upward movement of the arm 39, as heretofore described, causes the link 70 to rotate the ratchet disk and cause the carriage to be fed forward.

In order to limit the downward movement of the arm 66, I provide the arm 39 with an off-set 40', see Fig. 3, and carried by the same pivot 71' on which the arm 39 is pivoted is an arm 72 which extends under the off-set 40' of the arm 39. The inner end of the arm 72 is provided with an opening through which a pin 73 passes, and said pin enters one of the series of openings 74 carried by the frame 75 bolted to the frame 7. The said series of openings 74, as shown, are arranged concentric to the pivot 71' of the arm 72, and thus the pin 73 is adapted to enter any one of said openings, as the arm 72 is raised or lowered. It will be seen that the raising of the arm 72 supports the link or rod 70 in an upward position, and does not give as long a throw of the lever 70, and thus the worm will only be turned a slight portion of a revolution and cause but a slight feed of the carriage. By placing the pin 73 of the arm 72 in the lower opening of the series of openings 74, it will be seen that the link 70 is allowed to drop, and thus the pawl engages the ratchet at a lower point, and the upward movement of the link 70 will therefore be greater, and the worm is given a greater part of a revolution, and the carriage necessarily moves a greater distance, and increases the thickness of the slice. By this adjustment, as will be seen, the raising or lowering of the arm 72 one opening, increases or decreases the thickness of the feed, and there being a number of openings, it is seen that slices of slight differences may be cut, or a very thin slice or a medium thick slice.

Having thus described my invention, what I claim and desire to secure by Letters Patent, is:—

1. A slicer, comprising a base, a frame supported by one end of the base, a swinging arm pivotally supported by the upper end of said frame, a sprocket wheel carried by the pivot of said arm on the outside thereof, a rotary knife carried by the lower free end of said arm, a sprocket wheel carried by said knife, a chain passing over said sprocket wheels carried by the knife and the pivoted arm, a gear carried by the upper sprocket wheel, a large gear mounted on said frame and meshing with the before-mentioned gear, a crank carried by the shaft of the large gear, and a link pivotally connected to the crank and its opposite end pivotally connected to the swinging arm intermediate its ends, and means for rotating the large gear, whereby the arm is rocked back and forth, and the knife simultaneously rotated.
2. A slicer, comprising a base, a frame supported at one end of the base, a swinging arm pivotally supported by the frame, a rotary knife carried by the lower end of said arm, means for rotating said knife, a crank carried by said frame, means for rotating said crank, and a link pivotally connected to said crank, and to the arm intermediate its ends, the pivots of the arm and crank so positioned that the arm travels slowly in one direction and returns rapidly in the opposite direction.
3. A slicer, comprising a base, a feed carriage carried by the base, a frame carried by one end of the base, a swinging arm carried by the frame, a rotary knife carried by the lower free end of the arm, means for rotating said knife, a crank pivotally connected to the frame, a link pivotally connecting said crank and the swinging arm, and means operated by the link for operating the feed carriage.
4. A slicer, comprising a base, a feed carriage carried by the base, means for moving said feed carriage forward, a frame carried by one end of the base, a swinging arm carried by the frame, a rotary knife carried by the lower end of the arm, means for rotating said knife, a crank pivotally connected to the frame, a link pivotally connecting said crank and arm, and a cam carried by the upper end of the link for operating said feed carriage moving means.
5. A slicer, comprising a base, a feed carriage carried by the base, means for moving said feed carriage forward, a frame carried by one end of the base, a swinging arm carried by the frame, a rotary knife carried by the lower end of the arm, means for rotating said knife, a crank pivotally connected to the frame, a link pivotally connecting said crank and arm, and a cam carried by the upper end of the link for operating said feed carriage, and means for regulating the amount of forward movement of the feed carriage.
6. A slicer comprising a base, a frame carried by one end of said base, a swinging arm carried by the frame, a rotary cutter carried

by the arm, means for swinging said arm and rotating the knife, a feed carriage carried by the base, means for moving said carriage on the base, an arm pivoted to the frame and in the path of travel of the swinging arm, and operatively connected to said carriage operating means.

7. A slicer comprising a base, a frame carried by one end of said base, a swinging arm carried by the frame, a rotary cutter carried by the arm, means for swinging said arm and rotating the cutter, a feed carriage carried by the base, a worm for moving said carriage on the base, an arm pivoted to the frame and in the path of travel of the swinging arm, and operatively connected to the worm.

8. A slicer comprising a base, a frame carried by one end of the base, a swinging arm carried by the frame, a rotary knife carried by the arm, means for rotating said knife and rocking the arm, a feed carriage carried by the base, a worm for moving said carriage on the base, a ratchet disk carried by the worm, an arm pivoted to the frame and having its outer end in the path of travel of the swinging arm, a link pivotally connected to the arm and having pawls in engagement with the ratchet disk whereby the upward movement of the swinging arm causes the carriage to feed forward.

9. A slicer comprising a base, a frame carried by one end of the base, a swinging arm carried by the frame, a rotary knife carried by the arm, means for swinging said arm and rotating the knife, a feed carriage carried by the base, a worm for moving said carriage a ratchet disk connected to the worm and adapted to move said carriage forward, an arm pivoted to the frame and in the path of travel of the arm-operating mechanism, a link connecting the said arm and the ratchet disk, whereby the carriage is fed forward during the backward movement of the swinging arm.

10. A slicer comprising a base, a frame carried by one end, a swinging arm carried by the frame, a rotary knife carried by the outer end of said arm, means for swinging said arm and rotating the knife, a feed carriage carried by the base and horizontally movable thereon, a worm for moving said carriage, a ratchet disk carried by the end of said worm, an arm pivoted to the frame and having its outer end in the path of travel of the means for swinging the swinging arm, a link pivotally connected to the said arm and having a pawl engaging the ratchet disk carried by the worm, and means for supporting the pivoted arm at any desired height, whereby the feed of the carriage is regulated.

11. A slicer, comprising a base, a frame carried by one end of the base, a rotary swinging knife carried by the frame, means for rotating and reciprocating said knife, a feed carriage carried by the base, a worm for

moving said carriage on the base, a ratchet disk carried by said worm, a pivoted member concentric with the ratchet disk, a pawl carried by said member, an upwardly-extending lever carried by the free end of said pivoted member, means for adjustably supporting the said lever, and for raising said lever during each reciprocation of the swinging arm.

12. A slicer, comprising a base, a frame carried by one end of the base, a rotary swinging knife carried by the frame, means for rotating and reciprocating said knife, a feed carriage on the base, a worm for moving said carriage on the base, a ratchet disk carried by the worm, a member pivoted concentrically to the disk, a pawl carried by the pivoted member and engaging the disk, an upwardly-extending lever carried by the free outer end of the pivoted member, an adjustable arm engaging the upper end of said lever and supporting the same at different heights, and means operated by the knife operating means for raising said lever, whereby the worm is rotated.

13. A slicer, comprising a base, a frame carried by one end of the base, a combined rotary and swinging knife carried by the frame, means for rotating and reciprocating said knife, a feed carriage on the base, a worm for moving said carriage on the base, a ratchet disk carried by the worm, a member pivoted concentrically to the disk, a pawl carried by said pivoted member, and engaging the disk, an upwardly-extending lever carried by the outer free end of the pivoted member, an arm pivoted to the frame, and passing under a projection carried by the lever and adapted to support the same, a removable pin carried by the free end of said arm and adapted to enter one of a series of the segmentally-arranged openings in the frame for raising or lowering the lever, and means operated by the knife operating means for raising said lever, whereby the worm is rotated and the feed carriage moved on the base.

14. A slicer, comprising a base a frame carried by one end of the base a swinging arm carried by the frame a rotary knife carried by the arm, means for swinging said arm and rotating the knife, a feed carriage horizontally movable upon the base, a worm carried by the base and parallel with the

feed carriage, a pivoted spring pressed member carried by the feed carriage and adapted to be held in engagement with the worm, and means operated by the means for swinging said arm for rotating said worm.

15. A slicer, comprising a base, a frame carried thereby, a swinging arm carried by the frame, a rotary knife carried by the arm, a feed carriage horizontally movable upon the base, a worm carried by the base and adapted to move the feed carriage, an upwardly extending lever having means at its lower end for rotating the worm, means for operating the lever, an arm pivotally connected to the swinging lever, a pivoted swinging arm extending under the first pivoted arm and a removable pin carried by the free end of the second pivoted arm and adapted to enter one of the series of openings in the base, whereby the lever is supported at different heights for limiting the throw of the lever.

16. A slicer, comprising a base, a frame carried by one end of the base, an arm pivotally mounted on the frame, a rotary cutter carried by the end of the swinging arm, a sprocket wheel carried by the cutter, a sprocket wheel loosely carried by the end of the pivot of the arm on the outside thereof, a sprocket chain passing around said sprocket, a gear wheel rigidly carried by the upper sprocket wheel, a second large gear meshing with the first gear, a crank carried by the shaft of the large gear wheel, a link pivotally connected to the outer end of said crank and having its opposite end pivotally connected to the swinging arm intermediate its ends, and means for rotating the large gear, the positioning of the swinging arm, the crank and the link connection between the crank and the swinging arm being such that the swinging arm is in its outward position when the crank and link are on a dead center, and the continued movement of the crank allowing the arm to drop backward, and thus giving a rapid return of the rotary knife.

In testimony whereof I affix my signature in presence of two witnesses.

EDWARD F. SMITH.
